TOY VEHICLE

Arthur R. Thomas, Detroit, Mich.

Application February 25, 1946, Serial No. 649,905

3 Claims. (Cl. 280—243)

1

This invention relates to toy vehicles, and in particular to hand-propelled toy vehicles.

One object of this invention is to provide a hand-propelled toy vehicle having an improved propulsion mechanism which is more easily operated by the user than previous toy vehicles.

Another object is to provide a hand-propelled toy vehicle wherein the power is transmitted from a pivoted hand lever to an axle of the vehicle by a novel mechanism including a rocking tri-pivotal member, whereby a greater mechanical advantage may be more conveniently exerted than in other such vehicles.

Another object is to provide a hand-propelled toy vehicle as set forth in the object immediately preceding, wherein the force is transmitted from the tri-pivotal member to the axle of the vehicle through a flexible member, such as a belt, coiled around a clutch-connected mechanism which permits driving motion in one direction only and which accordingly permits the hand lever to be returned to its forward position without requiring the operator to exert effort.

Another object is to provide a hand-propelled toy vehicle as set forth in the two preceding objects, wherein the clutch mechanism also prevents the transmission of power backward from the axle to the hand lever when the vehicle is pushed backward.

Another object is to provide a hand-propelled toy vehicle wherein the hand lever carries a steering device which is connected to a steerable wheel of the vehicle through a novel flexible coupling.

Another object is to provide a hand-propelled toy vehicle wherein the mechanism employed enables a smooth operation with no dead center effect, and an unusually short stroke of the hand lever provides a long propelling stroke wherein the vehicle will advance a longer distance than prior vehicles for each stroke and whereby the user can operate the hand lever while standing up as well as sitting down.

Other objects and advantages of the invention will become apparent during the course of the following description of the accompanying drawings, wherein:

Figure 1 is a side elevation of a hand-propelled toy vehicle according to a preferred embodiment of the invention;

Figure 2 is a top plan view of the toy vehicle shown in Figure 1;

Figure 3 is a horizontal section through the clutch and adjacent structure taken along the line 3—3 in Figure 1;

2

Figure 4 is a vertical section through the clutch taken along the line 4—4 in Figure 3;

Figure 5 is a vertical section through the power-transmitting strap and shaft, taken along the line 5—5 in Figure 3;

Figure 6 is a vertical section adjacent the coil spring of the clutch shaft taken along the line 6—6 in Figure 3;

Figure 7 is an approximately vertical section through a portion of the steering mechanism, taken along the bent line 7—7 in Figure 1;

Figure 8 is an enlarged vertical section through the flexible coupling in the steering mechanism, taken along the line 8—8 in Figure 7; and

Figure 9 is a cross section through the steering shaft and adjacent mechanism, taken along the line 9—9 in Figure 1.

Referring to the drawings in detail, Figures 1 and 2 show a hand-propelled vehicle according to a preferred embodiment of the invention as including a pair of roughly triangular spaced frame members 10 having upper portions 11, forward portions 12 and lower portions 13 surrounding an aperture 14 of roughly triangular shape.

The frame portions 12 are curved as at 15 to permit swinging of the front tire 16 on the front wheel 17, which is rotatably mounted on the front axle 18 supported by the front fork 19. The latter at its upper end carries a shaft 20 (Figure 7) mounted in bores 21 and 22 of a rectangular frame 23, the sides of which are bolted as at 24 to the parallel projecting portions 25 of the frame members 10. The fork 19 and its shaft 20 are held together with the frame 23 by means of a nut 26 threaded upon the threaded portion 27 of the shaft 20.

Mounted on the upper end of the shaft 20 (Figure 8) and pinned thereto by the pin 28 is a collar 29 serving as an abutment member for oppositely coiled outer and inner coil springs 30 and 31 respectively. The outer coil spring 30 is seated against an annular shoulder 32, and is threaded upon the coarse outer threads 33 of a tubular projection 34 of the collar 29. The tubular projection 34 (Figure 8) is also provided with a coarse internally-threaded bore 35 forming a socket into which the lower end of the inner coil spring 31 is threaded. The lower end of the coil spring 31 is seated at the bottom 36 of the bore 35.

The upper ends of the outer and inner coil springs 30 and 31 are similarly threaded upon the external and internal threaded portions 37 and 38 respectively of a tubular extension 39 on a collar 40 which is pinned as at 41 to the reduced diameter portion 42 of a squared shaft 43 (Fig-

ure 8). The latter is reciprocably mounted in the square bore 44 in a sleeve 45 mounted in the lower end of a tubular shaft 46 (Figures 7 and 9). The tubular shaft 46 at its upper and lower ends is provided with enlargements 47 and 48 serving as abutments for upper and lower bearing brackets 49 and 50 respectively. The tubular shaft 46 is journaled in the bearing brackets 49 and 50 and on its upper end carries a cross bar 51. The brackets 49 and 50 are interconnected by a tie bar 52 connected thereto as by welding. The upper bracket 49 is provided with rearwardly extending ears 53 which are bolted as at 54 to the parallel side bars 55 of a hand lever generally designated 56.

The side bars 55 of the hand lever 56 are interconnected by a U-shaped member 57 welded thereto (Figure 2), and below this have outwardly bent portions 58 leading to the parallel lower portions 59 thereof. The lower side bar portions 59 are pivotally mounted on a pivot bolt 60 extending between the lower frame portions 13 of the frame members 11.

As a consequence of this construction, when the cross bar 51 is pulled back and forth, the hand lever 56 swings back and forth around the pivot bolt 60, its rearward position being indicated by the chain line in Figure 1. At the same time, the coil springs 30 and 31 flex and the squared shaft 43 slides in and out of the square bore 44 in the sleeve 45. This provides a constant steering connection between the front fork 19 and the cross bar 51, regardless of the position of the hand lever 56, and when the cross bar 51 is turned to steer the vehicle, the oppositely coiled coil springs 30 and 31 transmit the steering torque to the front fork 19 in either direction of turning, and in any position of the hand lever 56.

The power from the hand lever 56 is transmitted to a pair of spaced tri-pivotal members 61 by means of links 62 pivotally connected at 63 to the side bar portions 59 and at 64 to the arms 65 (Figure 1) of the tri-pivotal members 61. The latter roughly resemble draftsman's triangles, the forward corners of which are interconnected by a pivot bolt 66 carrying links 67, the opposite ends of which are pivotally mounted on the pivot bolt 68 interconnecting the lower forward end of the bottom portions 13 of the frame members 11. The tri-pivotal members 61 are also interconnected by a second pivot bolt 69 which carries a pair of links 70, the lower ends of which are pivotally mounted on a pivot bolt 71. The pivot bolt 69 is located approximately at the second corner of each tri-pivotal member 61, the third corners of which are interconnected by a tie bolt 72.

The end of a belt 73 is anchored to the bolt 72 and, after passing around the tie bolt 72, is secured as at 74 to the remaining portion of the belt 73. As a consequence, when the cross bar 51 and hand lever 56 are rocked to and fro, the tri-pivotal members 61 swing between their solid line and chain line positions shown in Figure 1, and the belt 73 is pulled forward and backward in accordance with the forward and backward motion of the tie bolt 72, the links 67 and 70 rocking about their respective pivot bolts 68 and 71.

The belt 73 near its opposite end is coiled around a hub 75 of a hollow shaft 76, the bore 77 of which rotatably engages a pivot bolt 78 secured to and extending between the side plates 79 and 80 which are in turn bolted as at 81 to the frame

members 11. The inner end 82 of the belt 73 is secured within a slot 83 in the hub 75 and held in position by a transverse set screw 84 countersunk therein (Figure 5). A disc-like flange 85 integral with the hollow shaft 76 (Figure 3) prevents the belt 73 from moving sidewise toward the side plate 80 as it uncoils in response to the motion of the hand lever 56.

A flat spiral spring 86 has its bent inner end 87 (Figure 6) seated in a slot 88 in the hollow shaft 76 and its outer end 89 is bent around an anchor bolt 90 secured as at 91 to the side plate 80 (Figure 3). As a result, the coil spring 86 winds up when the belt 73 is pulled forward and rotates the hollow shaft 76. When the hand lever 56 is pushed forward, the spiral spring 86 unwinds and pulls the belt 73 back into its coiled position upon the hub 75.

The hollow shaft 76 on the side opposite the coil spring 86 from the hub 75 is provided with a squared portion 92 engaging a correspondingly squared bore 93 in an eccentric cam 94 having a pair of spiral outer surfaces 95, the adjacent ends of which are separated by teeth 96 (Figure 4) forming notches 97 in the cam 94. These notches 97 are engaged by similarly shaped teeth 98 upon the forward ends of arcuate driving shoes 99, the rearward ends 100 of which are rounded. The arcuate outer surfaces of the shoes 99 engage the correspondingly arcuate inner surfaces of a pair of arcuate driven clutch members 101. These are floatingly mounted for limited self-alignment by being provided with squared transverse holes 102 penetrated by the projecting ends of smaller-diameter pins 103, the opposite ends of which are seated in bores 104 in the hub 105 of a sprocket 106 provided with the usual peripheral teeth 107. The square holes 102, being larger than the pins 103, permit both radial and tangential motion to a limited extent without binding, whereas round holes, while usable, increase the tendency to bind in a radial direction.

The hub 105 is provided with a hollow cylindrical bore 108 which receives the cam 94, the shoes 99 and the arcuate driven members 101 (Figure 3) and is provided with an end surface 109 against which the sides of these elements abut. The outer end of the bore 108 is closed by a cover plate 110 mounted on the annular shoulder 111 of the hollow shaft 76 and having a peripheral flange 112 extending over a portion of the hub 105 to enclose the chamber formed by the bore 108 therein.

The teeth 107 of the sprocket 106 are engaged by an endless sprocket chain 113 which drivingly engages the teeth 114 of a sprocket 115. The latter is mounted upon the tubular hub 117 of the rear wheel 118, carrying a tire 119. The hub 117 is provided with a bore 120 through which passes the rear axle 121 which in turn is adjustably mounted at its opposite ends in slots 122 in side plates 123 bolted as at 124 to the frame members 11. The rearward ends of the side plates 123 are bent perpendicularly as at 125 and bored for the passage of the threaded portion of eye-bolts 126, the eye portions of which encircle the opposite ends of the axle 121. Nuts 127 threaded upon the eye-bolts 126 serve to adjust the axle 121 forwardly or rearwardly in the slots 122 and thereby tighten or loosen the sprocket chain 113.

The hub 117 is provided with a brake housing 128 (Figure 2) containing conventional brake mechanism (not shown) and operated by a brake lever 129 to which is pivotally connected one end of a brake rod 130, the opposite end of which is

pivotedly connected to a crank arm 131, the hub of which is mounted upon a cross shaft 132 journaled in the opposite frame members 11. The right-hand end of the cross shaft 132 is bent to form an arm 133, the end of which is again bent as at 134 to provide a foot pedal portion. As a consequence, when the user pushes the foot pedal portion 134 downward, the cross shaft 132 is rotated, swinging the crank arm 131 and pulling the brake rod 130 forward, swinging the brake arm 129 and applying the brake to the rear hub 117.

To support the operator, the frame members 11 are provided with parallel upwardly projecting portions 135 (Figure 1) forming seat posts, the top ends of which carry angle brackets 136 fastened thereto. Fastened to the angle brackets 136 is a seat 137 for the operator. Footboards 138 are bolted to angle brackets 139 which in turn are bolted to the outer side of the frame portions 13 for supporting the feet of the operator.

The operations of the various subassemblies of the mechanisms associated with the toy vehicle of this invention have been described in connection with the description of their construction and consequently it is only necessary to describe the operation of the vehicle as a whole. The operator seats himself astride the vehicle, sitting upon the seat 137 and grasps the cross bar 51, which it will be assumed is in its forward position as shown in the solid line position of Figures 1 and 2. To propel the vehicle, the operator pulls the cross bar toward himself, swinging the hand lever 56 into the chain line position in Figure 1. This rocks the tri-pivotal members 61 around their supporting links 67 and 70 which swing forwardly into their chain line position. This action swings the tie bolt 72 and consequently pulls the belt 73 from its rearward position to its forward chain-line position, uncoiling the belt from the hub 75 and rotating the latter, together with the tubular hollow shaft 76 and cam 94.

As the lobes of the cam 94 rotate counterclockwise (Figure 4), they move toward the teeth 98, the inner surfaces of which are on a smaller radius of curvature than the surfaces adjacent the rounded ends 100 of the shoes 99. As a consequence, the shoes 99 are forced outwardly into driving engagement with the inner surface of the arcuate driving members 101, rotating them by the frictional engagement therebetween. This rotation is transmitted to the pins 103 and thence to the sprocket 106, rotating the latter in a counterclockwise direction (Figure 1). The consequent travel of the sprocket chain 113 likewise rotates the rear sprocket 115 and rear hub 117 in a counterclockwise direction, similarly rotating the rear wheel 118 and propelling the vehicle in a forward direction. As the vehicle gathers speed and consequently acquires stability, the operator is enabled to remove his feet from the ground and rest them upon the foot boards 138.

To steer the vehicle, the operator merely turns the cross bar 51 in the desired direction toward which the vehicle is intended to turn. The turning of the tubular shaft 46 is transmitted through the squared shaft 43 to the upper collar 40 and thence through the outer and inner coil springs 30 and 31 to the lower collar 29 and thence to the shaft 29 and front fork 19. The turning of the front fork 19 turns the front wheel 17 and consequently steers the vehicle in the di-

rection toward which the cross bar 51 is turned.

As previously stated, the steering connection is maintained between the cross bar 51 and the front fork 19 regardless of the position of the hand lever 56 by reason of the reciprocation of the squared shaft 43 within the square-bored sleeve 45 mounted within the tubular shaft 46 and also by the flexible connection provided by the outer and inner coil springs 30 and 31 and their associated elements. Thus, the vehicle may be steered, regardless of whether the hand lever 56 is in its forward, solid-line position, or in its rearward, chain-line position. The provision of the tri-pivotal members 61 and their associated elements provides a powerful mechanical advantage whereby the thrust arising from the swinging of the hand lever 56 rearwardly is transmitted to the belt 73 and thence to the sprocket 115 and rear wheel 118.

The coil spring 86 pulls the belt 73 rearwardly to rewind it upon the hub 75 and at the same time pulls the tri-pivotal members 61 and hand lever 56 from their rearward-chain-line-positions to their forward-solid-line-positions (Figure 1). To continue the propulsion of the vehicle, the operator merely continues to pull the hand lever 56 repeatedly in a rearward direction, the coil spring 86 each time returning it to its forward position as previously described. When he so desires, the operator applies the brake to the rear wheel 118 by depressing the foot pedal portion 134 of the cross shaft 132 in the manner previously described.

While I have shown and described my invention in detail, it is to be understood that the same is to be limited only by the appended claims, for many changes may be made without departing from the spirit and scope of my invention.

What I claim is:

1. A toy vehicle comprising a frame, forward and rear wheels mounted on said frame, a hand lever pivotally mounted on said frame, a unidirectional clutch device drivingly connected to one of said wheels, a pair of upstanding links pivotally mounted at their lower ends on spaced pivots on said frame, a tri-pivotal member having three pivots thereon arranged in a substantially triangular disposition, said tri-pivotal member having two of its pivots respectively connected to the upper ends of said links and having its third pivot pivotally connected to said hand lever, and an elongated flexible driving member connected at one end to said tri-pivotal member at a location spaced apart from the pivots of said tri-pivotal member on said links and at its other end connected to and coiled around a portion of said clutch device.

2. A toy vehicle comprising a frame, forward and rear wheels mounted on said frame, a hand lever pivotally mounted on said frame, a unidirectional clutch device drivingly connected to one of said wheels, a pair of upstanding links pivotally mounted at their lower ends on spaced pivots on said frame, a tri-pivotal member having two of its pivots respectively connected to the upper ends of said links and having its third pivot connected to said hand lever, and an elongated flexible driving member connected at one end to said tri-pivotal member at a location spaced apart from the pivots of said tri-pivotal member on said links and below a line joining said last-mentioned link pivots, said flexible driving member at its other end being connected to and coiled around a portion of said clutch device.

3. A toy vehicle comprising a frame, forward

and rear wheels mounted on said frame, a hand lever pivotally mounted on said frame, a unidirectional clutch device drivingly connected to one of said wheels, a pair of upstanding links pivotally mounted at their lower ends on spaced pivots on said frame, a tripivotal member having three pivots thereon arranged in a substantially triangular disposition, said tripivotal member having two of its pivots respectively connected to the upper ends of said links, a third link pivotally connecting the third pivot on said tripivotal member with a pivot on said hand lever, and an elongated flexible driving member connected at one end to said tripivotal member at a location spaced apart from the pivots of said tripivotal member on said pair of upstanding links and at

its other end connected to and coiled around a portion of said clutch device.
